UNITED STATES PATENT OFFICE.

HARRY P. COE, OF PAINESVILLE, OHIO, ASSIGNOR OF ONE-HALF TO ALEXANDER S. WILLIAMS, OF LONG ISLAND CITY, NEW YORK.

DRIER.

1,138,086.

Specification of Letters Patent.

Patented May 4, 1915.

Application filed August 7, 1912. Serial No. 713,763.

To all whom it may concern:

Be it known that I, HARRY P. COE, a citizen of the United States, residing in Painesville, Lake county, State of Ohio, have invented certain new and useful Improvements in Driers, of which the following is a specification, reference being had to the accompanying drawings, which form a part hereof.

10 This invention relates especially to driers for sheets of pulp, etc., and has for its object to improve generally the construction and efficiency of such apparatus, especially with respect to the driving of the feed rolls, the utilization of the warm air currents and the introduction of the wet material into the drier at different levels.

15 In accordance with the invention the upper rolls are no longer driven by the lower rolls but instead are driven positively by suitable mechanism which may or may not serve also to actuate the lower rolls.

20 A further improvement resides in the driving of alternate rolls by independent driving means placed on each side of the drier so that large power-transmitting devices, such as sprocket wheels, may be employed while only half of the driving load need be thrown on the prime mover, the remaining carrier rolls in such circumstances being permitted to run idle.

25 In order to utilize the air currents to the best advantage the present invention includes the provision of delivery pipes branching from the main air pipe and extending substantially parallel to the air flues of the drying chamber, and provided at frequent intervals with depending ducts which extend downward through the air flues to 30 points adjacent the bottom thereof. Suitable openings are provided in these ducts at various levels with respect to the feed rolls, which openings may be controlled by rotatable sleeves to permit the air to be directed 35 in its course through the drying chamber.

40 In order to render the vertical ducts and rotatable sleeves readily accessible separate removable panels are placed in the outer walls of the air flues.

45 Still another feature of the invention lies in the provision of a lifting table, provided with a bed of rolls on roller bearings, which is adapted to receive sheets of wet material from the wet machine or press and to be 50 raised to any desired level of carrier rolls in the drier before the material is fed there-

in. By this arrangement the capacity of the apparatus is greatly increased as sheets of pulp or the like may be fed simultaneously through the drying chamber on the several 55 series of carrier rolls at different levels.

The invention will be explained more fully with reference to the accompanying drawings in which:

Figure 1 is a view in side elevation of a 60 complete apparatus embodying the invention. Fig. 2 is a view in plan of the improved lifting table, a portion of a wet sheet and the wet mill being indicated. Fig. 3 is a view of the same in end elevation. Fig. 4 65 is a view in plan of a drier embodying the invention, part of the top wall being broken away to show the interior. Fig. 5 is a view of the same in side elevation, part of the 70 side walls being removed to show the interior. Fig. 6 is a view in vertical section through the drying chamber showing the 75 disposition of the air ducts, one of the ducts being shown in elevation. Fig. 7 is an enlarged detail view of one of the vertical 80 air ducts and rotatable sleeves, taken on the plane indicated by the line 7—7 of Fig. 6. Fig. 8 is a fragmentary view in section taken on the vertical axis of the same.

— The foundation, longitudinal base members *a*, vertical standards *b*, upper longitudinal frame member *c* and other such structural elements need not be described particularly herein since the invention has to do with certain features hereinafter to 85 be pointed out, the apparatus being in general similar to that used heretofore.

The apparatus shown in Fig. 1 comprises a wet mill *d*, shown in part, which feeds forward sheets *d'* of wet material on to a 90 lifting table *e* having a bed of rollers whence they pass into the drier. The lifting table comprises suitable frame members *e²* and a vertically movable platform *e³* on which is disposed a plurality of rolls *e⁴* freely revolvable on roller bearings *e⁵* of the usual type. Hence it will be understood that the sheets of wet material may be fed forward on the base with a minimum expenditure of power and without impairing the shape of the 95 sheets or the condition of the material by the imposition of undue strains. When the sheet *d'*, which is preferably cut to a proper length before delivery, is deposited on the table the platform *e³* thereof may be raised 100 so that the sheet although heavy and soft may be delivered quickly to each set of rolls 105 110

in the drier in turn. Or, under some circumstances, it may be desirable to have the sheet pass through a particular zone in the drier, and by the lifting table the sheet can be delivered readily to any zone, depending upon conditions.

The mechanism for elevating and lowering the movable platform may be of any approved type, the simple form herein illustrated comprising sustaining cables f attached to the corners of the platform e^3 and extending vertically upward over suitable sheaves f' to a windlass shaft f^2 having spools f^3 to receive the cables. This windlass shaft may be actuated by a sprocket and chain drive g through a hand wheel g' mounted on one of the frame members e^2 and preferably within convenient reach of the operator. When conditions warrant it, counterweights f^4 may be used to assist in the reciprocating movement of the table e , although it is to be understood that the invention is not limited to the structural details of the lifting table and its actuating mechanism.

Referring now to Figs. 4 and 6 particularly, it will be seen that the main air pipe h does not extend throughout the length of the drier as in former constructions, but instead communicates with two branch delivery pipes h' which extend substantially parallel to the sides of the drier and are preferably disposed directly above the air chambers k . Each of these branch pipes h' is provided with a plurality of vertical conduits h^2 which extend downwardly and through the air chambers k to points adjacent the bottoms thereof. These conduits h^2 may be provided with segmental openings h^3 preferably located opposite each pair of rolls so as to insure intimate contact of the air with the wet material. In previous constructions the air, having once been discharged into the air chambers, followed its own course through the drier to the stack, with the result that some of the same was not passed over the wet material while other portions passed longitudinally thereof, becoming unduly laden with moisture before escaping from the stack. To insure the highest efficiency in this respect the air, in the present invention, is not only conducted through the depending ducts h^2 and discharged at points adjacent the wet material, but revoluble sleeves h^4 having relatively narrow slits h^5 therein encircle the ducts about the segmental openings h^3 , the sleeves being supported in any suitable manner as by studs h^6 carried by the ducts. Thus it will be obvious that the direction of flow of the air discharged through the slits h^5 with respect to the longitudinal axis of the drier, may be controlled absolutely and currents set up in the chamber which will best serve to absorb the

moisture from the sheets therein, the air escaping later through a stack l . Varying conditions will govern the direction which it is desirable to give these currents of air, but by means of the construction herein employed their angular relation with respect to the longitudinal axis of the drier may be changed within a wide range. The several sleeves h^4 may be manually controlled by removing one of the panels m of which the outer walls of the air chambers k may be composed largely, the panels being held in position normally by suitable retaining means, here shown as wing nuts m' . This construction permits ready access to not only the air ducts but to the rolls and driving mechanism, as will later appear.

In Fig. 5 is shown most clearly the improved driving mechanism for the rolls and the interior of the drying chamber, Fig. 4 showing also the alternate-roll drive feature. On the standards b are mounted several series of lower rolls p and corresponding series of upper rolls q , the latter being provided at one end with sprockets q' engaged by endless chains r passing over idlers r^1 and r^2 at one end, and over driving sprockets r^3 mounted on the prime mover shaft r^4 at the opposite end, of the drier. Each alternate lower roll p is also provided with a sprocket p' for engagement with one of the chains r , each of the latter driving one series of lower rolls p and the upper rolls q of the next lower series. It will be understood that these rolls revolve in opposite directions, with the result that each of the coacting pairs of rolls serves to draw the wet material through the drier.

The intermediate lower rolls p^2 , which are not driven in conjunction with the upper rolls q , are provided at the end opposite the sprockets p' of the rolls p with similar sprockets p^3 engaged by chains r^5 which may be, and as shown, are actuated by the prime mover shaft r^4 .

By reason of the novel driving mechanism above described larger sprockets may be employed than hitherto by reason of the spacing of the same; smaller rolls may be used if desired, since the sprockets may be relatively larger, and the greater relative movement between the upper and lower series of rolls is possible since the movement of the former is not dependent upon the intermeshing of spur gears with gears on the latter, as formerly.

It is to be understood that it is unnecessary for a positive drive of both of the chains r^2 and r^5 to be used constantly since the latter may be disengaged from the driving shaft r^4 and the rollers p^2 be permitted to run idle during the movement of the wet material. In cases where, by reason of the peculiar nature of the material being dried, it is desirable to employ a maximum grip-

ping surface and driving power these intermediate rolls p^2 may be used as before explained, the chain r^5 being then driven positively. It will be equally obvious that independent prime movers may be provided for the driving chains on opposite sides of the drier, although in such cases it is desirable to have the same operate synchronously so that there may be no undue strains placed on the material. As in former constructions, steam headers n , having longitudinal steam pipes n' passing between the rolls, are provided behind the end plates o of the drying chamber.

15 The features of construction constituting the subject matter of this invention are peculiarly susceptible to modification in structural details, but all such modifications are to be considered within the scope 20 of the invention, provided the improvements in the apparatus herein sought to be made, are realized.

What I claim is:

1. In a drier, the combination of a drying 25 chamber, horizontal rows of pairs of transversely extended feeding rolls in said chamber, the lower roll of each alternate pair having a sprocket wheel fixed on one end, an endless sprocket chain associated with each 30 horizontal row of lower rolls and engaging with all of the sprocket wheels in the row, a driving sprocket in one loop of each sprocket chain and an idler sprocket wheel in the other loop of each sprocket chain.

35 2. In a drier, the combination of a drying chamber, horizontal rows of pairs of transversely extended feeding rolls in said chamber, the lower roll of each alternate pair having a sprocket wheel fixed on one end, an 40 endless sprocket chain associated with each horizontal row of lower rolls and engaging with all of the wheels in the row, a sprocket wheel fixed on the opposite end of each intermediate roll in each lower row, a 45 second endless chain engaging each of the last named sprocket wheels and means to drive said sprocket chains.

3. In a drier, the combination of a drying 50 chamber, horizontal rows of pairs of transversely extended feeding rolls in said chamber, the lower roll of each alternate pair having a sprocket wheel fixed on one end, an endless sprocket chain associated with each horizontal row of lower rolls and engaging 55 with all of the sprocket wheels in the row, a sprocket wheel on each upper roll of each pair of rolls with each of which said chain engages to drive the same, a driving sprocket in one loop of each sprocket chain and an

idler sprocket wheel in the other loop of 60 each sprocket chain.

4. In a drier, the combination of a drying chamber, horizontal rows of pairs of transversely extended feeding rolls in said chamber, the lower roll of each alternate pair 65 having a sprocket wheel fixed on one end of it, an endless sprocket chain associated with each horizontal row of lower rolls and engaging with all of the sprocket wheels in the row, a sprocket wheel on each upper roll 70 with each of which said chain engages to drive the same, a sprocket wheel fixed on the opposite end of each intermediate roll in each lower row, a second endless chain engaging each of the last named sprocket wheels 75 and means to drive said sprocket chains.

5. In a drier, a drying chamber, air chambers extending longitudinally thereof, a main air supply pipe, auxiliary air supply pipes in communication with said main air supply 80 pipe and extending longitudinally of the drier, conduits depending from said auxiliary supply pipes and extending vertically downward through said air chambers to points adjacent the bottoms thereof and having 85 openings for the discharge of air.

6. In a drier, a drying chamber, air chambers extending longitudinally thereof, a main air supply pipe, auxiliary air supply pipes in communication with said main air 90 supply pipe and extending longitudinally of the drier, conduits depending from said auxiliary supply pipes and extending vertically downward through said air chambers to points adjacent the bottoms thereof, and 95 having openings for the discharge of air, and valves to control the discharge of air through said openings.

7. In a drier, a drying chamber, air chambers extending longitudinally thereof, a main air supply pipe, auxiliary air supply pipes in communication with said main air supply pipe and extending longitudinally of the drier, conduits depending from said auxiliary supply pipes and extending vertically 100 downward through said air chambers to points adjacent the bottoms thereof, openings in said depending conduits for the discharge of air, and rotatable sleeves encircling said conduits about said openings and having 105 slits therein whereby the direction of discharge of the air may be controlled.

This specification signed and witnessed this 6th day of August, A. D. 1912.
